United States Patent Office

Des. 196,414
Patented Sept. 24, 1963

196,414

HAIR DRYER OR SIMILAR ARTICLE

John A. Russo, Bridgeport, Conn., assignor to General
Electric Company, a corporation of New York

Filed Nov. 5, 1962, Ser. No. 72,391

Term of patent 14 years

(Cl. D86—10)

Fig. 1.

Fig. 2.

Fig. 3.

Fig. 4.

*Fig. 5.*FIG. 1 is a top plan view of a hair dryer embodying my new design;

FIG. 2 is a left side elevational view of the hair dryer of FIG. 1;

FIG. 3 is a right side elevational view of the hair dryer of FIG. 1;

FIG. 4 is a bottom plan view of the hair dryer of FIG. 1; and

FIG. 5 is a rear elevational view of the hair dryer as shown in FIG. 1.

The essential features of the design reside in the full-line showing.

I claim:

The ornamental design for a hair dryer or similar article, substantially as shown and described.
